UNITED STATES PATENT OFFICE.

HARRY ZAMSKY AND SOL LEVY, OF NEW YORK, N. Y.

DESIGN FOR A UTILITY-STAND FOR DESKS.

58,415.

Specification for Design.

Patented July 12, 1921.

Application filed December 14, 1920. Serial No. 430,759. Term of patent 3½ years.

To all whom it may concern:

Be it known that we, HARRY ZAMSKY and SOL LEVY, citizens of the United States, residing at New York city, in the county and State of New York, have invented a new, original, and ornamental Design for a Utility-Stand for Desks, of which the following is a specification, reference being had to the accompanying drawing, forming a part thereof.

The figure is a perspective view of a utility stand for desks showing our new design.

We claim:—

The ornamental design for a utility stand for desks as shown.

HARRY ZAMSKY.
SOL LEVY.

Witnesses:

LILLIAN KUSLAN,
IRVING J. SAMSKY.
